UNITED STATES PATENT OFFICE.

LOUIS S. SAYLOR, OF INDIANAPOLIS, INDIANA, ASSIGNOR OF TWO-THIRDS
TO JACKSON SAYLOR AND JOHN THOMAS, BOTH OF SAME PLACE.

ROLLING-MILL HOOKING AND CARRYING MACHINE.

SPECIFICATION forming part of Letters Patent No. 320,973, dated June 30, 1885.

Application filed February 7, 1885. (No model.)

To all whom it may concern:

Be it known that I, LOUIS S. SAYLOR, of the city of Indianapolis, county of Marion, and State of Indiana, have invented certain new and useful Improvements in Rolling-Mill Hooking and Carrying Machines, of which the following is a specification.

In operating old-style rolling-mills one of the most laborious and severe parts of the work is that which has been known as "hooking"—that is, raising and lowering the blooms and partly-rolled rails as they are run through the rolls—and much time and labor have been spent to produce satisfactory machinery for performing the work. This is the object of my present invention, and said invention principally consists in tables mounted on tracks running along parallel with the rolls, provided with rollers mounted on swinging arms, and mechanism for driving said tables back and forth and raising and lowering said rollers.

It further consists in certain details of construction and arrangement of parts, as will be hereinafter more particularly described.

Referring to the accompanying drawings, which are made a part hereof, and on which similar letters of reference indicate similar parts, Figure 1 is a top or plan view of the rolls of a rolling-mill and the appliances and mechanism adjacent thereto, my invention being embodied therein; Fig. 2, a side elevation of the same, as seen from the dotted line *z z* in Fig. 1; Fig. 3, a similar view to a portion of Fig. 1 on an enlarged scale; Fig. 4, a front elevation of the mill, showing one table in transverse section, as seen from the dotted line *y y*; Fig. 5, a transverse vertical sectional view looking to the right from the dotted line *x x* in Fig. 3; Fig. 6, a transverse vertical sectional view looking toward the left from the dotted line *w w* in Fig. 3; Fig. 7, a similar view to Fig. 5, except it is shown as when looking to the left from the dotted line *x x*, with the rollers in the tables raised; Fig. 8, a detail perspective view of the mechanism for driving the rollers in one of the tables when said table is in a certain position; Fig. 9, a transverse sectional view through one of the eccentrics; Fig. 10, a longitudinal sectional view of the

same and adjacent parts, and Fig. 11 a detail 50 vertical sectional view of the stop for one of the eccentric-shafts.

In said drawings the portions marked A represent the foundation and frame-work to the mill; B, the roll-housing; C, the tracks 55 upon which the tables are mounted; D E, said tables; F, a shaft by which, through rack-bars or other suitable connection, said tables are driven back and forth; G' G'', shafts carrying eccentrics for raising and lowering the 60 rollers of the tables; G, a shaft for operating said cam-shafts; H, a shaft from which the shafts F G are driven; I, a drive-roll shaft, and J a shaft by which the rollers on the table on the front side of the roll are driven when 65 said table is brought into position alongside them.

The foundation and frame-work A are suitably arranged to support the roll-housings, tracks, tables, and the various mechanisms for 70 operating the same, as will be readily understood, and not being peculiar except in their adaptability to the arrangement of mechanism illustrated, they will not be further described herein.

The roll-housings B, the roughing-rolls B', and finishing-rolls B'', mounted therein, are or may be of the ordinary or any well-known form, and will be readily understood by an examination of the drawings.

The tracks C for the tables are arranged alongside, a suitable distance from, and parallel to the rolls upon bearings in the foundation or frame-work A, provided therefor. They support and guide the tables D and E as 85 they move back and forth in front of the rolls. The top edges of said tracks, upon which the tables directly rest, are A-shaped to fit into similarly-formed notches in the under side of the frame-work of the tables, and said tables 90 are thus held in exact position thereon.

The tables D and E, as before indicated, rest and move upon the track C, being preferably provided with small trucks e to facilitate this operation. They are driven by the 95 shaft F through long rack-bars D' and E', rigidly connected thereto, which engage with spur-pinions f on said shaft.

The table D is provided with a set of swinging arms, d , the lower ends of which are pivoted to the frame-work of the table, and are provided with bearings upon the upper ends 5 in which rest the rollers D^2 . These arms are connected together so that they will rise and fall in unison, carrying the rollers with them, and are operated through rods g by eccentrics g' upon the shaft G' , said shaft G' being 10 driven by the shaft G . This table is also provided with guide sides D^3 , which are also mounted on the upper ends of the swinging arms, and are thus operated to rise and fall with the rolls. Upon the ends of the shafts of 15 the rollers D^2 are placed miter gear-wheels d^2 , which are adapted, when the table reaches the position directly in front of the roughing-rolls B' , to engage with similar miter-gears, j , on the shaft J . At the same time projecting arms d^3 20 on the side of the table D engage with the upper end of the lever D^4 , drawing it to one side, which, through the connecting-rod d^4 and the clutch-lever J' , operates the clutch J^2 to engage with the loose miter-gear j^2 upon 25 the end of the shaft J , which is constantly engaged with a similar miter gear, i , on the shaft I , and thus driven, said clutch J^2 being prevented from rotating on the shaft J by a spline in the usual manner, while being permitted 30 a free endwise movement thereon. By this arrangement, as will be readily seen, the shaft J is permitted to remain stationary at all times except when the table comes into the described position, when it is set in motion, and 35 the rollers in said table driven thereby, thus operating to carry the bloom or partly-rolled rail into the desired pass of the rolls of the rolling-mill, and upon said table being moved away from said position the arms d^3 therein 40 operated to disengage the clutch and permit said shaft J to again become motionless.

The table E is operated generally in much the same manner as is the table D, being provided with a set of rising and falling arms, e , 45 carrying rollers E^2 , which are operated in the same manner through rods g by cams g^2 on the shaft G^2 , said shaft G^2 being also driven by the shaft G . The sides E^3 of this table correspond to the sides D^3 of the table D, and may either 50 be mounted and operated in the same manner, or may be simply extensions of the sides of the table as the rollers of this table receive rails from the rolls only when in depressed position. This table E has projecting portions upon its outer end carrying pins e' , which are adapted to engage, as the table reaches the position behind the finishing-rolls, with a permanent table-section, E^4 , carrying rollers also mounted on pivoted swinging arms, and thus, 55 as the rollers of this table are raised when in the stated position, the rollers of said permanent table-section are raised with them, and thus the length of this table is increased practically in this position to any desired extent. 60 The shaft F is arranged transversely to the rolls and extends across from one side to the

other, and carries the pinions f , by which, through the rack-bars D' and E' , the tables D and E are driven. It is operated by a friction-clutch, F' , between the two parts of which 70 is a suitable pinion on the end of the shaft F^2 , running at right angles with said shaft F , said shaft F^2 being driven from the operating-shaft H , its end carrying the pinion being adapted to be moved back and forth, so as to bring said 75 pinion into contact with one or the other of the clutch parts by means of a rod, f^2 , running to an operating-lever, F^3 . Thus, as will be readily seen by an examination of the drawings, especially Fig. 3, by simply pushing or 80 pulling on the lever F^3 the shaft F can be driven in one or the other direction, and the tables D and E moved back and forth along the tracks.

The shaft G runs parallel with the shaft F , 85 and through suitable gears drives the shafts G' and G^2 , carrying the eccentrics g' and g^2 , by which the rollers in the tables are lifted or depressed. Two loose pulleys, g^3 and g^4 , upon said shaft are driven in opposite directions 90 by a suitable arrangement of belts, as shown, and between them upon the shaft is a double-faced clutch, which is prevented in the usual manner from revolving loosely on the shaft by means of a spline, and which may be operated by a lever, g^5 , to engage with a clutch-face upon either of said pulleys. A connecting-rod, g^6 , runs from said lever to an operating-lever, g^4 , situated near the lever F^3 , and by means of which said clutch can be thrown 95 into or out of engagement with either of said pulleys g^3 or g^4 , and the shaft G thus driven into either direction. Thus the same operator that handles the lever F^3 can by similarly operating the lever G^4 revolve the shafts G' and 100 G^2 and raise or lower the rollers in the tables. The eccentrics g', g^2 are mounted between downwardly-projecting portions on the frame-work of the tables, as shown most plainly in Fig. 10, and are thus carried back and forth along 105 the shafts with said tables, being loosely mounted so as to permit this operation. They are prevented from turning, however, by long splines in said shafts, which are shown most plainly in Figs. 9 and 10. Upon the ends of 110 said shafts G' and G^2 which are farthest from the shaft G are placed arms g^7 , which are adapted, when the rolls have been raised to the utmost height and the eccentrics have just passed the center, to come in contact with and be 115 supported by suitable stops, A' , said stops being arranged in suitable position on the foundation or frame-work, and being preferably spring-stops, as shown in Fig. 11, in order to prevent a too violent concussion as the arms 120 strike them.

The shaft H is an ordinary driving-shaft, and receives its motion either from the roll-shaft or from the engine, or any other suitable source, and is connected by suitable gears and 125 belts with the shafts F and G , thus imparting motion thereto.

The shaft I is a stationary shaft, carrying ordinary driving-rolls arranged in front of the rolls of the mill, and, like the shaft H, is driven from any suitable or desired source.

- 5 The operation of my said invention may be recapitulated as follows: The rolls and the driving-shaft H being in motion, and the tables in the position shown most plainly by the full lines in Fig. 3 and in Figs. 5 and 6, the bloom 10 as it comes from the tracks is run onto the table D, and the rollers of said table being in motion they carry it forward toward the rolls, being assisted during the latter part of this operation by the feed-roll I' on the shaft I. Upon 15 leaving the rolls the now partly-rolled rail comes onto the table E, when the operator, standing by the levers F³ and G⁴, pushes upon the lever G⁴, throwing the clutch G³ into engagement with the pulley g³, thus setting the 20 shaft G in motion, and, through the shafts G' and G², the eccentrics thereon, the connecting-rod g, and the swinging arms on the tables, raising the rollers in said tables up to a height level with the upper passes in the rolls. As 25 soon as the partly-rolled rail is received on the table E and said table has been raised the operator pushes upon the lever F³, throwing the friction-clutch on the shaft F into engagement, and thus moving the tables somewhat 30 along the tracks, bringing the partly-rolled rail in front of the next pass. The operator, standing near the table E, then starts the partly-rolled rail back through said pass, whence it is delivered again to the table D. 35 The operator, standing near the levers, then pulls upon the lever G⁴, throwing the clutch G³ into engagement with the pulley g⁴, which revolves the shafts G, G', and G² in the opposite direction, lowering the rolls to their former level. The partly-rolled rail is then 40 pushed onto the next lower pass, and this operation is continued until the rail is finished. When the rail reaches the last pass of the finishing-roll, it being by this time of considerable length, and needing a longer support than the table itself, the table E couples onto the table-section E⁴, as before described, and raises the rolls thereof as though said section were a part of itself. Thus it will be seen that by 45 the use of my invention a single operator by proper manipulation of levers is enabled to raise and lower the blooms or partly-rolled rails, as may be desired, and to move them from one position to another in relation to the 50 rolls as may be necessary to bring them in line with the proper pass.
- Having thus fully described my said invention, what I claim as new, and desire to secure by Letters Patent, is—
- 60 1. The combination, with the rolls of a rolling-mill, of tables mounted on tracks parallel with said rolls and provided with rollers mounted on swinging arms, and cam-shafts for operating the same, for the purposes specified.
- 65 2. The combination, with the rolls of a roll-

ing-mill, of traveling tables mounted on tracks parallel with the rolls, and rollers therein mounted on pivoted swinging arms, shafts running parallel with the tracks carrying eccentrics, and connecting-rods connecting said eccentrics with said swinging arms.

3. The combination of the rolls of a rolling-mill, tables mounted on tracks parallel with said rolls, a shaft running transversely of said 70 rolls and tracks and connected to each of said tables, and a clutch whereby the direction of rotation of said shaft may be reversed, and said tables thus moved in either direction along said tracks, substantially as set forth.

4. The combination, in a rolling-mill, of tables for handling the partly-rolled rails, mounted on tracks parallel with the rolls, a shaft, F, carrying pinions f, rack-bars secured to said tables and engaging with said pinions, 85 a clutch, F', a connecting-rod, f', and a lever, F³, by which the same may be operated, substantially as shown and described, and for the purposes specified.

5. The combination, in a rolling-mill, of 90 tables for handling the partly-rolled rails, rising and falling rollers therein, shafts carrying eccentrics for operating said rising and falling rollers, a shaft, G, running transversely of the mill and engaging with each of said shafts, 95 the loose pulleys on said transverse shaft running in opposite directions, each provided with a clutch-face, the clutch arranged between them, a connecting-rod, and an operating-lever for operating said clutch, substantially as set forth.

6. The combination, in a rolling-mill, of 100 tables for handling the partly-rolled rails, mounted on tracks parallel with the rolls and provided with rising and falling sets of rollers, shafts carrying eccentrics for operating 105 said rollers, said shafts being provided with arms g¹, for limiting their movement, and stops A', for limiting the movement of said shafts, substantially as set forth.

7. The combination, in a rolling-mill, of 110 the table E, for assisting in handling the partly-rolled rails, mounted on tracks running parallel with the rolls and provided with pins e or similar engaging devices, and a permanent table-section, E⁴, said table E, when it reaches the proper position, being adapted, by means of said pins, to engage with said table-section, and both being provided with rising and falling rollers, which, when the two are 120 engaged, are thus adapted to move simultaneously, substantially as shown and described, and for the purposes specified.

8. The combination, in a rolling-mill, of a 125 table, D, having rollers therein, the shafts of said rollers being provided with miter-gears d², and a shaft, J, running transversely of said rollers, and provided with similar miter-gears with which the miter-gears on the roller-shafts will engage when the table is brought into 130 proper position, whereby said rollers may be driven by said shaft, said shaft J being also

provided with a loose gear and a clutch operated by the table, substantially as set forth.

9. The combination, in a rolling-mill, of a table, D, mounted and adapted to run on tracks and provided with rollers, the shafts of which are provided with gears on their ends, a transverse shaft, J, provided with similar gears and also with a loosely-mounted gear, and a clutch, said loosely-running gear being 10 in engagement with a continuously-moving gear, arms d' on said table, a pivoted lever, D', with which said arms are adapted to engage, a pivoted lever, J', connected to said

clutch, and a connecting-rod, d', connecting said two levers, whereby as said table comes 15 into position said clutch is operated to engage with said loosely-running gear and said shaft, and through it the rollers in the table set in motion, substantially as set forth.

In witness whereof I have hereunto set my 20 hand and seal, at Indianapolis, Indiana, this 28th day of January, A. D. 1885.

LOUIS S. SAYLOR. [L. S.]
